(57) **CLAIM**

The ornamental design for a toilet brush with holder, as shown and described.

DESCRIPTION

FIG. 1 is a perspective view of a toilet brush with holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the toilet brush with holder.

The broken lines in the drawings depict portions of the toilet brush with holder that form no part of the claimed design.
